Franklin Bache Satterthwaite, Short Hills, N. J.

Application April 23, 1946, Serial No. 128,897

Term of patent 3½ years

(Cl. D25—1)

To all whom it may concern:

Be it known, that I, Franklin B. Satterthwaite, a citizen of the United States, residing at Short Hills, in the county of Essex and State of New Jersey, have invented a new, original, and ornamental Design for a Game Block, of which the following is a specification, reference being had to the accompanying drawing, forming a part thereof.

I claim:

The ornamental design for a game block, as shown.

FRANKLIN BACHE SATTERTHWAITE.
